UNITED STATES PATENT OFFICE.

CHARLES S. BLOSE, OF PALMERTON, PENNSYLVANIA.

TWO-CYCLE GAS-ENGINE.

1,073,086.

Specification of Letters Patent. Patented Sept. 16, 1913.

Application filed November 5, 1912. Serial No. 729,639.

To all whom it may concern:

Be it known that I, CHARLES S. BLOSE, a citizen of the United States, residing at Palmerton, in the county of Carbon, State 5 of Pennsylvania, have invented certain new and useful Improvements in Two-Cycle Gas-Engines; and I do hereby declare the following to be a full, clear, and exact description of the invention, such as will enable 10 others skilled in the art to which it appertains to make and use the same.

This invention relates to gas engines and has for an object to provide a gas engine having no moving valves.

15 A further object of the invention is to provide a novel arrangement of intake and exhaust ports which coact with a piston having a port in one side to control the supply of fuel.

20 A further object of the invention is to provide a novel valve controlled fuel bowl having novel connection with the inlet ports of the engine and operated by the pressure and suction of the engine piston to supply the 25 fuel to the engine.

With the above objects in view the invention consists of certain novel details of construction and combination of parts herein-after fully described and claimed, it being 30 understood that various modifications may be made in the minor details of construction within the scope of the appended claim.

In the accompanying drawings forming part of this specification: Figure 1 is a side 35 elevation of the engine. Fig. 2 is a longitudinal sectional view through the engine with the piston at its lower limit of stroke. Fig. 3 is a longitudinal sectional view through the engine with the piston at its 40 upper limit of stroke. Fig. 4 is a vertical sectional view taken on the line 4—4 Fig. 1. Fig. 5 is a cross sectional view on the line 5—5 Fig. 2. Fig. 6 is a longitudinal sectional view through the fuel tank. Fig. 7 45 is an enlarged longitudinal sectional view through the fuel bowl. Fig. 8 is a detail perspective view of the piston. Fig. 9 is a cross sectional view taken on the line 9—9 Fig. 7. Fig. 10 is a sectional view on the 50 line 10—10 Fig. 2.

Referring now to the drawings in which

like characters of reference designate similar parts, the engine is shown to comprise a water jacketed cylinder 10 having on one side a bypass 11 which communicates with the cylinder through ports 12 and 13 as usual in 2 cycle gas engines, there being a cover plate 14 over this bypass, the cover plate being equipped with spaced openings 15 and 16 the purpose of which will presently appear. This bypass will be herein-after referred to as a charge box. Formed in the wall of the cylinder diametrically opposite the ports 12 and 13 are ports 17 and 18, the upper port 17 being an exhaust port, 65 and the lower port 18 being an air intake port for admitting air to the crank case 19.

Within the cylinder a piston 20 is mounted having the usual deflector 21 on the top, the piston being cylindrical in form, and being provided in one side with a port 22 which is adapted to alternately register with the ports 12 and 13 of the charge box. The piston is equipped with the usual piston rod 23 which is connected in the ordinary manner to the crank shaft 24.

A fuel bowl 25 is arranged adjacent to the charge box and includes a float chamber having a transparent cylindrical wall 26 which is closed at the top and the bottom by 80 closures 27 and 28 respectively, the upper closure being centrally bored to receive the stem 29 of a float 30, this stem extending through the float and terminating in a ball valve 31. Upon raising of the float the ball 85 valve seats in a conical seat 32 formed in a tubular depending extension 33 on the bowl bottom. An oil supply pipe 34 is connected to the extension by means of a nut 35 and within the mouth of this pipe a ball valve 36 90 is confined by a screen 37 and gravitates upon a conical seat 38 to normally close the supply pipe.

A lateral tubular extension 39 is formed on the bottom of the fuel bowl and communicates with a feed pipe 40 which is terminally equipped with a nozzle 41 having discharge branches 42 which enter the port 15 of the charge box and spray the fuel into the engine cylinder through the intake port 12 100 thereof. A needle valve 43 is threaded into the bore of the nozzle to regulate the flow of

fuel therethrough. The fuel bowl is provided in the top with a tubular extension 44 to which a pipe 45 is connected, this pipe leading to the opening 16 of the charge box 5 and conducting the vacuum and pressure of the crank case to the fuel bowl to operate the float as will presently appear. The top and bottom closures 27 and 28 of the feed bowl are clamped together by clamp bolts 46 10 and by these bolts the closures are drawn tight against the ends of the transparent wall 26.

The fuel supply pipe 34 is branched at the end as shown at 47 and 48, which branches 15 communicate respectively with a gasolene compartment 49 and kerosene or similar cheap oil compartment 50 of a tank 51, both branches being provided with valves 52. A valve controlled drain pipe 53 opens through 20 the bottom of the fuel bowl and opens into the kerosene compartment 50, and is utilized to drain the fuel bowl of kerosene when it is desired to start the engine using gasolene as will presently appear.

25 The operation of the gas engine is as follows: In Fig. 3 the piston 20 is shown at top of stroke having compressed the gas mixture above it into combustion space C ready to be ignited by electric spark of spark plug 54. Now since the crank case 19 is gas tight, a vacuum or suction has been caused below in space G which is relieved when piston is up as shown, the lower edge of the piston having uncovered the air intake port 18 allowing fresh air to rush into the crank case and hollow piston.

As the piston moves down it closes the air intake port 18 compressing the air charge held in the crank case space G. Just before 40 it reaches its lowest point shown in Fig. 2, its upper edge first uncovers exhaust port 17 allowing burnt gases to rush out into the air and next uncovers charge box port 12 letting in the fresh gas charge while at the 45 same time the piston port 22 comes into registration with the charge box port 13 and the air which is being compressed below the piston escapes up through the charge box and into the space C above the piston 50 carrying with it the fresh gas charge as shown in dotted lines.

As the piston moves up, the piston port 22 and charge box are covered first and finally the intake and exhaust ports 12 and 55 17 are covered with a resultant compression of the charge confined above the piston. This up-stroke of the piston as above stated creates a vacuum in the crank case, and it will now be noted that the port 14 of the 60 charge box is located considerably below the air intake port 18 so that the charge box port is exposed before the air intake port with a resultant suction through the feed

bowl pipe 45 and drawing in of fuel to a normal level in the feed bowl, and upon this 65 level being reached the float automatically closes the inlet to the bowl. This normal level is reached just as the vacuum in the crank case is relieved by the exposing of the air port 18 when the piston passes there- 70 beyond on its up-stroke.

During the down-stroke of the piston a portion of the compressed air below the piston will pass through the registering piston port 22 and charge box port 13 into the feed 75 bowl pipe 45 with a resultant pressure on the fuel and resultant forcing out of the fuel through the pipe 40 into the charge box where it is carried up into the compression space of the cylinder by the re- 80 maining portion of the compressed air from the crank case as above stated.

It will here be stated that upon the normal level of fuel in the feed bowl being reached the float will close the bowl inlet and after 85 a predetermined amount of fuel has been blown from the feed bowl into the engine the float sinks and drops the ball valve 31 away from its seat to permit of the normal fuel level being restored upon the next suction through the pipe 45. The purpose of the ball 36 is only for holding the fuel in the bowl after it is once admitted, as without this ball check the fuel would return to the tank at each pressure through the pipe 45. 90

It will thus be seen that a gas engine has been produced which is devoid of moving valves and that by the peculiar arrangement of the intake and exhaust ports together with the ported piston, and by the 100 coaction of these parts, the fuel supply is automatically controlled.

It has been found by experiment that after the engine has been started on gasolene, the gasolene supply may be shut off 105 and the cheaper oil supply turned on, there being no appreciable difference in the speed of the engine, but there being an appreciable difference in the cost of running the engine with the cheaper oil over the more expensive 110 gasoline.

The inner walls of the piston are provided with ribs as shown to facilitate cooling of the piston, the air from the crank case circulating between these ribs on the down 115 stroke of the piston.

What is claimed, is:—

In a gas engine, a cylinder, a crank case, a hollow piston having a port in one side, a bypass in said cylinder, said piston port 120 being adapted to momentarily register with the lower end of said bypass, a float controlled fuel supply device, a fuel discharge pipe communicating with said device and with the upper end of said bypass, a combined pressure and vacuum conducting pipe 125

connected to said device and entering the lower end of said bypass, and operating on said float to control the flow of fuel through said discharge pipe, an exhaust port in said cylinder, and an air intake port in said cylinder alternately exposed and sealed by said piston to admit air to said crank case.

In testimony whereof, I affix my signature, in the presence of two witnesses.

CHARLES S. BLOSE.
